CLAIM

The ornamental design for a free-weight, as shown and described.

DESCRIPTION

FIG. 1 is a perspective view of the free-weight showing my new design;

FIG. 2 is a front elevation view of the free-weight showing my new design;

FIG. 3 is a top plan view of the free-weight showing my new design;

FIG. 4 is a side elevation view of the free-weight showing my new design; and,

FIG. 5 is a bottom plan view of the free-weight showing my new design.

The broken lines illustrate portions of the article that form no part of the claimed design.
